UNITED STATES PATENT OFFICE.

ORLANDO J. BOOS, OF LOS ANGELES, CALIFORNIA.

CONVEYER.

Application filed March 16, 1920. Serial No. 366,346.

To all whom it may concern:

Be it known that I, ORLANDO J. Boos, a citizen of the United States, residing at Los Angeles, in the county of Los Angeles and 5 State of California, have invented new and useful Improvements in Conveyers, of which the following is a specification.

This invention relates to conveyers and more particularly to a combined vertical 10 and horizontal conveying system for the efficient handling of objects to be transported from one level to another as from one story to another in buildings and from one discharge end of the vertical transfer on to 15 means for making a horizontal transfer; and the invention consists of the construction, the combination and in details and arrangements of the parts an embodiment of which invention is illustrated in the accompanying drawings and described and claimed herein.

Figs. 1, 1^A and 1^B are fragmentary views showing when combined an elevational and partially sectioned view of the vertical and 25 horizontal conveying means.

Figs. 2 and 2^A are vertical elevation and sectional views of fragments of the apparatus looking in a plane at right angles to Fig. 1.

30 Fig. 3 is a plan and sectional view on line 3—3 of Fig. 1^A; and Fig. 3^A is a continuation of Fig. 3.

Fig. 4 is a section on line 4—4 of Fig. 1.

Fig. 5 is a side elevation and partial sectional view of the head structure of the vertical conveying means.

The apparatus is primarily designed for the transfer of soiled dishes in public or private institutions where the soiled dishes 40 are to be carried from an upper floor to a lower floor in large quantities with as rapid action as is consistent with safety and economy and are to be transferred from the discharge end of the vertical conveying means 45 in a substantially horizontal plane to a wash room where the soiled dishes are automatically discharged from the horizontal conveyor and may be rapidly collected and conveyed to dish washing apparatus; and with 50 the above objects in view the invention involves an organized and concurrently driven set of vertical and horizontal conveying mechanisms deriving power from a common source and all properly timed so as to efficiently handle the objects to be transferred.

The system may be driven by power derived from a motor 2, Fig. 1^A, the pulley of which drives a belt 3 engaging and driving a larger pulley 4 secured on a shaft 5 on which there is provided a worm 6 engaging 60 a worm wheel 7, Fig. 2^A, secured on a countershaft 8, the shafts 5 and 8 being suitably journaled and supported on a substantial framework generally indicated at 9 and comprising such upright and such horizontal members as may be requisite according to the installation of the system.

One end of the counter shaft 8 is provided with a pinion 10 engaging a bevel gear 11 secured on a transverse shaft 12 mounted in 70 suitable bearings 13 provided on the framework, and the bevel gear 11 engages and drives a pinion 14 secured on an oblique shaft 15 in suitable bearings 16. On the lower end of the shaft 15 there is secured a 75 pinion 17 engaging a corresponding pinion 18 secured on a transverse shaft 19 having suitable bearings in the frame.

On the transverse shaft 12 there is secured a pair of sprocket wheels 20 and each of these engages a respective sprocket chain 21 and 22 extending in parallelism upwardly and engaging head sprockets 23 secured on a head shaft 24 mounted in adjustable bearings 25 engaged by jack screws 26 mounted 80 in fixed nuts or threaded parts 27 attached to the head structure of the frame 9.

The set of chains 21—22 is transversely connected at suitable points by substantial plates hereinafter termed runners designated 90 at 30, these plates being connected to the respective chains by carrier blocks 31 provided on the chains 21—21, and the runners have on their front faces bracket arms 32 which arms together with the runner plates 30 95 may be secured to the carrier blocks 31 as by bolts 33. The runner plates 30 are normally positioned to lie substantially flatwise along and across the connected portions of the chains 21 and 22.

As clearly shown in Fig. 5 the brackets 32, a set of which is attached to the outer face of each runner 30, have, each, a pivot 34 on which there is mounted a swinging arm 35 preferably made of channel cross section so that the flanges straddle the sides of the respective arms 32, and the web portion of each arm 35 is designed to be supported upon the upper surface of the bracket 32 when the several arms 35 are positioned as 105 110

shown in Fig. 5 and on the downwardly moving stretch of the conveyer chains 21-22.

As shown in Figs. 1 and 4, the vertical 5 conveyer belts 21 and 22 pass along vertical guide rails or corner tracks 36, the upwardly moving stretches of the conveyer chains being shown to the left of Fig. 1 and the chains shown as bearing against the adjacent 10 corner tracks 36 while the downwardly moving stretches of the chains on the right-hand side of the column structure are caused to move in a common vertical plane as the runner members or plates 30 pass into a channel 15 formed by suitable guide means comprising angle members or tracks 37 having flanges spaced suitably from the adjacent flanges of the contiguous corner tracks 36 so that the downwardly moving stretches 20 of the sprocket chains 21-22 successively bring the runners 30 from an indeterminate position on the upwardly moving stretches over the head sprocket wheels on the shaft 24. As the plates enter the guide- 25 ways formed by the guide rails 36-37 the runners become vertically disposed with the bracket arms 32 extending horizontally and with the arm members 35 resting horizontally thereon in a coordinate position. So 30 that a tray, indicated at T in dotted lines in certain of the figures, can be readily supported in a horizontal position on a group of the arms 35 as the successive group of arms move into register with the wall opening, indicated at W in Fig. 1, that is ar- 35 ranged at any suitable elevation and at a convenient loading station to permit the trays or carriers in which the objects to be transferred are placed.

40 The supporting arms 35 are preferably provided with a cushioning or padding means such as a strip of leather or other suitable material indicated at 35^a appropriately attached to the arms and forming 45 therefor a bed on which the receptacle T may rest.

The downwardly moving groups or sets of carrying arms 35, which arms in a common group are suitably spaced as plainly shown in Fig. 4, pass a horizontal plane in which there is arranged a horizontal conveying means comprising a set of sprocket chains 40, there being shown in Fig. 3 a set comprising four of the chains each chain arranged in a vertical plane with its length arranged and guided over a series of sprocket and guide wheels.

The chains 40 have a downwardly extending bight in Fig. 1^a passing around a master 60 or driving sprocket 41, of which there is one for each chain 40, these sprockets being secured on the shaft 19 that is driven by the bevel pinion 17-18. The chains 40 each pass downwardly to the master sprocket 65 wheels 41 from idler wheels 42 on a trans-

verse shaft 43 and pass diagonally from the master sprocket wheels 41 up to a set of guide wheels 44 each individually supported on a bracket arm 45 extending from a suitable support 46 so as to hold the wheels 44 in the spaces between the carrying arms 35 of each group of arms, so that as the arms 35 of a group carrying a receptacle T pass below the top horizontal stretches of the belts 40 the carrier or tray will be deposited on these upper and co-planar stretches which move in the direction indicated by the arrow a, Fig. 1^a, to convey away horizontally the deposited receptacles or trays.

The horizontal stretches of the conveying 80 chains 40 are each supported and guided in trough-shaped guides 47 extended to a suitable distance and terminating at a discharge station indicated at D in Fig. 3^a which is a continuation of Fig. 3. The bottoms of the 85 guide rails 47 may be provided with a renewable liner such as a strip or strips of wood indicated at 47^a.

At the discharge station or end of the conveyer 90 there is arranged a deflector 48 in the form of an upright cam or fixed guide flange beneath the lower edge of which the several conveyer chains 40 pass around a contiguous direction wheel 49 on a shaft 50 mounted on adjacent posts of the frame 9. 95 From the direction wheels 49 the chains pass over idlers 51 mounted on a common cross shaft 52 and thence to other idlers 53 also on a common shaft 54 and thence to the direction wheels 42.

The deflecting flange or cam member 48 is obliquely disposed so as to intercept the incoming trays T and divert them on to the receiving table or bench B from which they may be carried to a dish washing machine or may be otherwise disposed of according to the nature of the objects being transferred and handled.

The bracket arms 35, while they are pivoted on the brackets 32 at the pivots 34, preferably have a sufficient friction between the connecting means so as to normally hold the arms 35 in the position shown in Fig. 1, but in the event of the apparatus becoming stalled and any obstacle engaging the bracket arms 35 these can yield upwardly as indicated by the arrow b, Fig. 5.

From the above it will be seen that I have provided an apparatus that is comparatively simple, that is reliable in operation and durable and effective and will handle rapidly and operate with large carrying capacity with a minimum of power consumption and also will operate to change the direction of travel or path in which the objects are being transferred.

The guide wheels 44 are, preferably, made in duplicate halves or sections and are arranged on opposite sides of the contiguous bearing forming portion of the end of its

respective bracket arm so that by this construction a minimum width of structure is secured as is desirable because of the projection of the bearing arms 45 with their pulleys or guide wheels 44 extending in between the carrying arms 35.

Various changes may be made without departing from the spirit of the invention as claimed.

10. What is claimed is:

1. A conveying apparatus comprising a vertically arranged set of chain conveyers with cross plates each arranged parallel to given carrier links of the chain, brackets attached to each plate, and receiving arms pivotally attached to the brackets.

2. A conveying system comprising a set of sprocket chains having bracket arms arranged to extend perpendicular to the chains, and another set of chains set at an angle to the first and having portions extended between the said bracket arms so that as the latter pass the extended portions of the chains the objects will be transferred from one to the other, the bracket arms being resiliently yieldingly attached to the respective chains of the second set.

3. A conveying system comprising a set of sprocket chains having bracket arms arranged to extend perpendicular to the chains, another set of chains set at an angle to the first and having portions extended between the said bracket arms so that as the latter pass the extended portions of the chains the objects will be transferred from one to the other, cross members connecting the sprocket chains, and guides for the said members whereby the arms are positioned in a predetermined manner for a portion of their orbital movement, said guides comprising channel members having a flared upper end to facilitate the entrance of said cross members into the guide portion of said channel members.

4. A conveying system comprising a vertically arranged set of chain-conveyers with cross plates each arranged parallel to given

carrier links of the chains; brackets attached to each plate; receiving arms pivotally attached to the brackets to lie in a common plane; and a set of conveyer chains at an angle to the vertical set and so arranged that the arms pass between the last named set to deposit objects thereon.

5. In a conveying apparatus, a series of spaced endless conveying belts arranged so as to have portions thereof in a common plane and having carrying arms which when moving in a portion of their orbit formed by the said common plane extend perpendicularly to the endless means; and a complementary set of transfer conveyers comprising endless traveling belts with supporting brackets projecting between the spaced arms of the other conveying means, the said brackets having end portions forming, each, a bearing for a respective sectional pulley, the sections of which are disposed on opposite sides of the projecting bearing portion of the bracket.

6. In a conveying apparatus, a series of spaced endless conveying belts arranged so as to have portions thereof in a common plane and having carrying arms which when moving in a portion of their orbit formed by the said common plane extend perpendicularly to the endless means; and a complementary set of transfer conveyers comprising endless traveling belts with supporting brackets projecting between the spaced arms of the other conveying means, the said brackets having end portions forming, each, a bearing for a respective sectional pulley.

7. A conveying apparatus comprising conveyers including endless traveling belts with supporting brackets, said brackets having end portions forming, each, a bearing for a respective sectional pulley, the sections of which are disposed on the opposite sides of the projecting bearing portion of the bracket.

In testimony whereof I have signed my name to this specification.

ORLANDO J. BOOS.
